U.S. PATENT DOCUMENTS

The ornamental design for a drill, as shown and described.

DESCRIPTION

D300,503 S	4/1989	Schultz
D335,073 S	4/1993	Anthony et al. D8/68
D339,046 S	9/1993	Fushiya et al. D8/68
D359,215 S	* 6/1995	Zurwelle D8/68
D378,268 S	* 3/1997	Schultz D8/68
D380,952 S	* 7/1997	Kim D8/68
D382,457 S	* 8/1997	Ghode et al. D8/68
D396,177 S	* 7/1998	Schultz D8/68
D402,871 S	* 12/1998	Clowers et al. D8/68

FIG. 1 is a front perspective view of a drill showing my new design.

FIG. 2 is a rear perspective view thereof.

FIG. 3 is a right side elevational view thereof.

FIG. 4 is a left side elevational view thereof.

FIG. 5 is a top plan view thereof.

FIG. 6 is a bottom plan view thereof.

FIG. 7 is a front elevational view thereof; and,

FIG. 8 is a rear elevational view thereof.
